UNITED STATES PATENT OFFICE

CHARLES W. TODD, OF SCHENECTADY, NEW YORK

JOURNAL HOUSING FOR AXLES OF LOCOMOTIVES AND RAILWAY CARS

Application filed July 11, 1930. Serial No. 467,225.

The present invention relates to appliances known as journal boxes or housings used in connection with axle journals for locomotives and railway cars.

5 The object of this invention is to provide a structure whereby the journal housing will be adaptable for easy removal from and replacement upon the journal and supporting frame, and to permit inspection and change 10 of parts when found necessary, and means for securing the housing when in use, against relative movement transversely of the vehicle and accidental disengagement of the housing from the frame. The invention is 15 particularly designed for such housings as contain an anti-friction bearing mechanism, such as the appliance described in my application for improvement in axle journal bearing, filed March 28th, 1928, Ser. No. 20 265,386, now Patent No. 1,797,301, granted Mar. 24, 1931. However in no sense is the invention limited to any particular type of anti-friction means and in the embodiment 25 described in the present case, a type generally known in the art is employed.

Other objects and advantages of this invention, relating to the particular arrangement and construction of the several parts, will become apparent as the following detailed description proceeds.

In referring to the drawing illustrating the invention, the scope whereof is defined by the appended claims:

55 Figure 1 is a vertical side elevation of the journal housing disposed within the frame pedestal; Fig. 2 is an end view of Fig. 1 partly in section; Fig. 3 is a fragmental plan view of Fig. 1; Fig. 4 is a partial vertical side elevation of the housing and frame, embodying a modification of the appliance shown in Figs. 1, 2 and 3; Fig. 5 is an end view of Fig. 4 partly in section on the line V—V of Fig. 4; and, Fig. 6 is an isometric 60 view of the combined shoe and locking device of the modification.

In the practice of the invention, referring descriptively to an approved embodiment thereof, which is herein exemplified, like parts being designated by like characters,

it is understood that the axle 1, is provided with a journal 1a, at each of its ends.

While the invention is designed for use in connection with axles having collarless journals, it is to be noted, at the outset, that there 55 may be modifications of other details in various instances, as for example, various designs of the frame pedestals with appropriate differences, will be employed, depending upon whether the invention is to be employed in connection with a locomotive, a 60 passenger or a freight car, or other vehicle. Furthermore, where the invention is employed either on standard equipment or old equipment for replacement, not only will 65 the frame pedestal be suitably designed, but the journal housing will likewise be suitably designed to accommodate it for use in such equipment. While in the embodiment 70 illustrated in the drawing the pedestals are formed integrally with the frame, it is also contemplated to employ the invention in connection with frame pedestals of the detachable type. Such further modifications of 75 minor details as may be necessary, will be well within the province of the mechanical skill of those versed in the art.

In the present case, two embodiments of the invention are illustrated in the accompanying drawing. In Figs. 1, 2 and 3, 80 the pedestal 3a for the journal housing 2, made integral with the frame 3, is a load supporting member, and is designed to bear on the housing 2. In Figs. 4 and 5 (illustrating the modification) the pedestal 3a is de- 85 signed to bear on a shoe 9 (Fig. 6), which is disposed beneath the frame and which in turn bears on the housing. In these embodiments of the invention as aforesaid, the axle 1, is provided with collarless journals 1a, which 90 offer no obstruction to the movement of the journal bearings and housings longitudinally over the axles. The frame pedestal 3a is provided with an extended lower portion 95 3b which allows a clearance space 6 between its inner sides and the housing, permitting a relative vertical movement, whereby the pedestal may be jacked up away from the axle journal in order to remove the housing or replace it upon the journal. The positive 100

locking bolt 10, shown in Figs. 1, 2 and 3, is also fitted with a clearance space, and the shoe 9 is allowed a revolving or vertical movement with the housing 2 when the frame separates from the housing. The horizontal movement of the housing 2 upon raising the frame pedestal for the purpose of removal or replacement of said housing, is dependent upon removal of the locking bolt 10, and in the modification, the supporting of the shoe vertically sufficiently to disengage the tongue on the housing (Figs. 4 and 5).

The collarless journal 1a, is reduced in diameter relative to the body of the axle 1. The journal housing 2, contains an anti-friction bearing mechanism, not shown, but which may be similar to that shown in my hereinbefore mentioned copending application and the exterior diameter of the housing is made of slightly less diameter than the inner sides of the frame pedestal 3a, thus permitting the housing 2 to move longitudinally on the axle journal 1a for insertion upon or removal from the same. The frame pedestal 3a surrounds the housing 2 on its top and sides and provides an opening 5 between its lower portions 3b, which extend inwardly so that the opening 5 is of less width than the horizontal exterior dimension of the housing 2, but of greater width than the exterior dimension of the axle journal 1a. Between the housing 2 and the extended lower portion 3b, of the frame pedestal 3a is the said space 6 provided to permit the relative vertical movement, whereby the frame pedestal 3a may be jacked up for removal of the housing 2 horizontally from or for replacement of the same upon the axle journal 1a. After the housing 2 is removed, the axle 1 may be removed from the frame 3 by passing the journal 1a vertically through the opening 5.

It is important that the housing be held against transverse movement relative to the locomotive or car when in use, and in the present instance, this is accomplished by cooperating tongue and groove members, tongue 7, (Figs. 1-3) being formed on top of the housing 2, laterally thereof, and groove 8 being formed laterally in the interior of the top wall of the frame pedestal 3a. Correspondingly, in the modification, (Figs. 4-6) the tongue 14 is formed on the top of the housing 2, laterally thereof, groove 15 is formed in the bottom of the shoe 9, groove 22 is formed in the upper side of the shoe, and tongue 21, is formed on the interior of the top wall of the frame pedestal 3a, the tongues and grooves cooperating with each other to prevent transverse movement of the housing relative to the locomotive or car.

The lugs 13 (Figs. 1-3) cast integral with the housing 2, lug 12 cast integral with the frame pedestal 3a and the bolt 10 disposed through channels in said lugs and secured

by an enlarged head 4, and the split key 11, form a positive lock, preventing accidental disengagement of the journal housing 2, from the frame pedestal 3a. Correspondingly, the shoe 9 is provided with a locking element 9a, (Figs. 4-6) cooperating with the lugs 18 on the frame and the pin 17, to secure the housing against accidental disengagement when the modified form of the invention is used. It will be apparent that while the housing of the embodiment shown in Figs. 1 to 3 inclusive, is locked against vertical movement relative to the frame, so as to prevent accidental transverse movement and disengagement, the housing of the modified form of the device illustrated in Figs. 4 to 6 inclusive, is not so locked, and may upon passing over uneven or rough track have a limited vertical movement with relation to the frame and move out of engagement with the top of the pedestal. Under these conditions, however, the shoe 9, by reason of its locking element 9a, will follow the housing, swinging on the pin 17, and prevent transverse disengaging movement of the housing. The pin with the locking element 9a will serve as a guide for the shoe in bringing the parts back together, and the shoe, as aforesaid, will secure the housing against accidental disengagement.

The locking element 9a is formed with an open end 16, to allow free movement with respect to the pin 17, which is secured in or cast integral with the lugs 18 on the frame pedestal 3a.

The open end 16 of the locking element 9a permits the shoe 9 to be applied to the frame pedestal 3a, through the opening 19, and the locking element passed over the pin 17, prior to the insertion of the housing 2, upon the axle journal 1a. A lever arm 20 is provided on the shoe 9 above the locking element 9a by which the shoe may be revolved about the pin 17, to vertically hold the groove 22 against the tongue 21 and provide clearance for the housing 2 for its insertion upon or removal from the axle journal 1a.

The invention claimed and desired to be secured by Letters Patent is:

1. In a locomotive or railway car, the combination of a supporting frame member having pedestal jaws providing a space therebetween open at the sides and bottom, a journal housing adapted for insertion into and removal from said space by horizontal movement transverse to said frame member through an open side of said space, said pedestal jaws engaging said housing to permit said housing to have vertical movement relative thereto, cooperating tongue and groove elements between said housing and said frame member for retaining the housing against transverse movement relative to the locomotive or car, engageable and disengageable by vertical movement, said disengag-

able vertical movement leaving the housing free to be horizontally moved transversely to the frame member from and into said space, and means for hingedly connecting 5 a part of the cooperating elements to guide said elements upon accidental vertical movement of the housing relative to the frame member and to prevent accidental transverse movement of the housing relative to the 10 frame member.

2. In a locomotive or railway car, the combination of a journal housing, means engaging said housing whereby said housing may have vertical movement relative 15 thereto, and cooperating tongue and groove elements between said housing and engaging means, one of which elements comprising a shoe for retaining the housing against transverse movement relative to the locomotive 20 or car, said tongue and groove elements being engageable and disengageable by said vertical movement, and said shoe being hingedly connected to said engaging means to guide said cooperating tongue and groove 25 elements in the return of said elements to cooperative engagement when accidentally disengaged.

3. In a locomotive or railway car, the combination of a journal housing, means engaging 30 said housing whereby said housing may have vertical movement relative thereto, cooperating tongue and groove elements between said housing and engaging means, one of which elements comprising a shoe for retaining the housing against transverse movement relative to the locomotive or car, said tongue and groove elements being engageable and disengageable by said vertical movement, a pin member on said engaging means, 35 and a lug element formed on the said shoe provided with an open side engaging said pin member to guide said shoe in the return of the tongue and groove elements to cooperative engagement when accidentally disengaged, and to permit free transverse movement 40 of said shoe in assembling said shoe on the pin.

4. In a locomotive or railway car, the combination of a journal housing, means engaging 50 said housing whereby said housing may have vertical movement relative thereto, cooperating tongue and groove elements between said housing and engaging means, one of said elements comprising a shoe for retaining the housing against transverse movement relative to the locomotive or car, said tongue and groove elements being engageable and disengageable by said vertical movement of the housing, a pin member on said 55 engaging means, a lug element formed on said shoe provided with an open side engaging said pin member to guide said shoe in the return of the tongue and groove elements to cooperative engagement when accidentally 60 disengaged, and to permit free transverse

movement of said shoe in assembling the same on the pin, and a lever arm extending from the shoe whereby the shoe may be revolved about said pin to vertically hold said shoe in raised position to provide clearance for said housing upon assembling or dissembling said housing.

5. In a locomotive or railway car, the combination of a journal housing, a supporting frame member having pedestal jaws providing a space therebetween open at the sides and bottom, said housing being adapted for insertion into and removal from said space by horizontal movement transverse to said frame member through an open side of said space, said jaws permitting vertical movement of the housing relative to said frame member, cooperating elements between said housing and said frame member for retaining the housing against transverse movement relative to the locomotive or car, engageable and disengageable by the vertical movement, said disengageable movement leaving the housing free to be horizontally moved transversely to the frame member from and into said space, and means hingedly connecting a part of the cooperating elements with the frame member to guide said elements upon accidental vertical movement of the housing relative to the frame member and to prevent accidental transverse movement of the housing relative to the frame member.

6. In a locomotive or railway car, the combination of a supporting frame member, an axle journal, a journal box providing a housing for an axle journal bearing, and a journal bearing, said frame member having a pedestal surrounding the top and sides of the box and providing an opening at the bottom of said pedestal of a width less than the horizontal exterior dimension of the journal box and greater than the exterior diameter of the axle journal.

7. In a locomotive or railway car, the combination of a supporting frame member, an axle journal, a journal box providing a housing for an axle journal bearing, a journal bearing, said frame member having a pedestal surrounding the top and sides of the box and providing an opening at the bottom of said pedestal of a width less than the horizontal exterior dimension of the journal box and greater than the exterior diameter of the axle journal, and means interposed between said frame and journal box for retaining said journal box against transverse movement relative to the locomotive or car.

8. In a locomotive or railway car, the combination of a supporting frame member, an axle journal, a journal box providing a housing for an axle journal bearing, a journal bearing, said frame member having a pedestal surrounding the top and sides of the box and providing an opening at the bottom of said pedestal of a width less than the horizontal

exterior dimension of the journal box and greater than the exterior diameter of the axle journal, and tongue and groove elements disposed between said box and pedestal co-operating with each other to prevent transverse movement of the box relative to the locomotive or car.

9. In a locomotive or railway car, the combination of a supporting frame member, an axle journal, a journal box providing a housing for an axle journal bearing, a journal bearing said frame member having a pedestal surrounding the top and sides of the box and providing an opening at the bottom 70 of said pedestal of a width less than the horizontal exterior dimension of the journal box and greater than the exterior diameter of the axle journal, tongue and groove elements disposed between said box and pedestal 75 co-operating with each other to prevent transverse movement of the box relative to the locomotive or car, and means hingedly connecting a part of the said cooperating elements and said pedestal to guide said cooperating elements and to hold said elements in cooperative engagement with the box upon accidental vertical movement of the box relative to the frame member, so as to prevent accidental transverse movement of the box relative to the frame member.

10. In a locomotive or railway car, the combination of a supporting frame member, an axle journal, a journal box providing a housing for an axle journal bearing, a journal bearing said frame member having a pedestal surrounding the top and sides of the box and providing an opening at the bottom of said pedestal of a width greater than the exterior diameter of the axle journal and less than the horizontal exterior dimension of the journal box, and cooperating elements between said box and said frame member for retaining the box against transverse movement relative to the locomotive or car, engageable and disengageable by vertical movement of the box relative to the pedestal.

11. In a locomotive or railway car, the combination of a supporting frame member, an axle journal, a journal box providing a housing for an axle journal bearing, a journal bearing said frame member having a pedestal surrounding the top and sides of the box and providing an opening at the bottom of said pedestal of a width greater than the exterior diameter of the axle journal and less than the horizontal exterior dimension of the journal box, and cooperating elements between said box and said frame member for retaining the box against transverse movement relative to the locomotive or car, engageable and disengageable by vertical movement of the box relative to the pedestal, and means for locking said box and frame to prevent accidental disengagement of said co-operating elements.

12. In a locomotive or railway car, the combination of a supporting frame member, an axle journal, a journal box providing a housing for an axle journal bearing, a journal bearing, said frame member having a pedestal surrounding the top and sides of the box and providing an opening at the bottom of the same of a width greater than the exterior diameter of the axle journal and less than the horizontal exterior dimension of the journal box, said box being permitted limited vertical movement relative to the pedestal and being adapted for insertion into and removal from the pedestal by horizontal movement transverse to the locomotive, co-operating elements between said box and said pedestal for retaining the box against transverse movement relative to the locomotive or car, said cooperating elements being engageable and disengageable by said limited vertical movement, lug members formed on said box and said pedestal and having orifices formed therein, and a pin engaged in said orifices, connecting said box and pedestal to hold the cooperating elements in engaged position and to prevent accidental transverse movement of the box relative to the said locomotive or car.

13. In a locomotive or railway car, the combination of a supporting frame member, an axle journal, a journal box providing a housing for an axle journal bearing, a journal bearing, said frame member having a pedestal surrounding the top and sides of the box and providing an opening at the bottom of said pedestal of a width greater than the exterior diameter of the axle journal and less than the horizontal exterior dimension of the journal box, said box being permitted limited vertical movement relative to the pedestal and being adapted for insertion into and removal from the pedestal by horizontal movement transverse to the locomotive or car, cooperating tongue and groove elements between said box and said pedestal for retaining the box against transverse movement relative to the locomotive or car, said cooperating tongue and groove elements being engageable and disengageable by said limited vertical movement, lug members formed on said box and said pedestal and having orifices formed therein, and a pin engaged in said orifices connecting said box and pedestal to hold the cooperating tongue and groove elements in engaged position and to prevent accidental transverse movement of the said box relative to the locomotive or car.

14. In a locomotive or railway car, the combination of a supporting frame member, an axle journal, a journal box providing a housing for an axle journal bearing, a journal bearing, said frame member having a pedestal surrounding the top and sides of the box and providing an opening at the bottom

tom of said pedestal of a width greater than the exterior diameter of the axle journal and less than the horizontal exterior dimension of the journal box, and cooperating tongue and groove elements formed on said box and frame member, cooperating with each other to prevent movement of said journal box transversely of the locomotive or car.

15. In a locomotive or railway car, the combination of a supporting frame member, an axle journal, a journal box providing a housing for an axle journal bearing, a journal bearing, said frame member having a pedestal surrounding the top and sides of the box and providing an opening at the bottom of said pedestal of a width greater than the exterior diameter of the axle journal and less than the horizontal exterior dimension of the journal box, and cooperating tongue and groove elements between said box and said pedestal for retaining the box against transverse movement relative to the locomotive or car, engageable and disengageable by vertical movement of the box relative to the pedestal.

16. In a locomotive or railway car, the combination of a supporting frame member, an axle journal, a journal box providing a housing for an axle journal bearing, a journal bearing, said frame member having a pedestal surrounding the top and sides of the box and providing an opening at the bottom of said pedestal of a width greater than the exterior diameter of the axle journal and less than the horizontal exterior dimension of the journal box, cooperating tongue and groove elements between said box and said pedestal for retaining the box against transverse movement relative to the locomotive or car, engageable and disengageable by vertical movement of the box relative to the pedestal, and means for locking said box and pedestal to prevent accidental disengagement of said cooperating elements.

45. 17. In a locomotive or railway car, the combination of a supporting frame member, an axle journal, a journal box providing a housing for an axle journal bearing, a journal bearing, said frame member having a pedestal surrounding the top and sides of the box, and said box being permitted limited vertical movement relative to the pedestal and being adapted for insertion into and removal from the pedestal by horizontal movement transverse to the locomotive or car, cooperating elements between said box and said pedestal for retaining the box against transverse movement relative to the locomotive or car, said cooperating elements being engageable and disengageable by said limited vertical movement, lug members formed on said box and said pedestal and having orifices formed therein, and a pin engaged in said orifices, connecting said box and pedestal to hold the cooperating elements in engaged

position and to prevent accidental transverse movement of said box relative to the locomotive or car.

18. In a locomotive or railway car, the combination of a supporting frame member, an axle journal, a journal box providing a housing for an axle journal bearing, and a journal bearing, said frame member having a pedestal surrounding the top and sides of the box and providing an opening at the bottom of said pedestal of a width greater than the exterior diameter of the axle journal and less than the horizontal exterior dimension of the journal box, said box being permitted limited vertical movement relative to the pedestal and being adapted for insertion into and removal from the pedestal by horizontal movement transverse to the locomotive or car.
